UNITED STATES PATENT OFFICE

2,161,827

FASTENING-INSERTING MACHINE

Fred N. La Chapelle and John W. Ashley, Beverly,
Mass., assignors to United Shoe Machinery Corporation,
Paterson, N. J., a corporation of New Jersey

Application April 27, 1936, Serial No. 76,577
Renewed July 15, 1938

125 Claims. (Cl. 1—32)

This invention relates to machines for inserting fastenings, it being especially applicable to the attachment of heels to shoes by the use of fastenings formed from strings of material, an instance of which type of fastening is disclosed in Letters Patent of the United States No. 1,729,169, La Chapelle, September 24, 1929.

In the heelng of shoes, the non-metallic fiber disclosed in the above-identified patent has many advantages. If the fastenings penetrate the heel-seat, they will not injure the foot of the wearer nor, if they are acted upon by perspiration, affect the shoe-material. When a heel is worn, they will not mar floors or produce sparks by which explosions might be caused. The holding power of such fastenings is great, and many of the difficulties encountered in feeding loose fastenings are avoided. The invention has as an object, the provision of an efficient and relatively simple machine by which fiber or like fastenings may be formed from strings of material, the work pricked to receive said fastenings, which are then inserted to complete an attaching operation. The work may involve, for example, the attachment of heel-bases to shoes, the securing of lifts to previously attached bases or the simultaneous attachment of bases and lifts. Herein, the invention is described in connection with the insertion of fastenings for securing rubber lifts to previously attached bases. More particularly, the invention involves the structure of both the inserting die with its heel-holder and the co-operating pricking and driving or inserting assembly and the facilitating of changes of these elements to give different inserting designs; the manner of actuating the transferring device or loader by which fastenings are severed from strings of material supplied by a feeder and delivered to the die for insertion; the control of the devices whereby the work is successively pricked and the fastenings driven into the pricked openings, this control including the insertion of fastenings of different lengths in the same piece of work; the production of an uninterrupted operating cycle, occurring in two stages; the supply to the fastenings of a liquid to increase their hold upon the work; and the feeding of strings for the production of the fastenings, this including the supplying of fastenings of different lengths and the limiting of delivery to but one stage of the operating cycle.

In the accompanying drawings, illustrating a specific embodiment of our improved fastening-inserting machine,

Fig. 1 is a broken front elevation of the upper portion of said machine;

Fig. 2, a similar view of the lower portion thereof;

Figs. 3 and 4, side elevations corresponding respectively to Figs. 1 and 2;

Fig. 5, a central, vertical, longitudinal section through the upper portion of the machine;

Fig. 6, a horizontal section on the line VI—VI of Fig. 5, with portions omitted;

Fig. 7, a perspective view of the die-block with its upper and lower portions separated;

Fig. 8, a broken front elevation of the feeding mechanism, and

Fig. 9, a vertical sectional detail through the liquid-supplying mechanism.

The principal supporting and actuating elements of the apparatus may be as in Letters Patent of the United States No. 446,885, Pope, February 24, 1891, this patent disclosing the well-known lightning heeler. Near the central portion of a frame 10 a die-block D is mounted horizontally, and at opposite sides of this block rods 12, 12 reciprocate vertically. Bridged across the upper extremities of the side-rods is a top-girt or bar 18 by which are supported vertical drivers 22 movable into and out of registering passages 24 in the die-block. These drivers and passages are disposed in accordance with a particular inserting design, the character of which depends upon the work to be done. The side-rods are secured at their lower ends in cross-head 25 guided for vertical movement in the frame, and reciprocated through an eccentric rod 26 from an eccentric 28 upon a horizontal driving shaft 30. Power is applied to the shaft by a pulley 32 through a clutch 34, this clutch being controlled by a hand-lever 36 which actuates a lever 38 (Fig. 4) to trip the clutch and cause the machine to perform a single operating cycle. Upon a cross-head 40 movable vertically in the frame 10 is a work-supporting jack 42 arranged to slide horizontally upon the cross-head from an outer position, in which the work is applied, to an inner fastening-inserting position beneath the die-block D. In the latter relation, it is located by an adjustable back-stop 44. To apply preliminary or measuring pressure to the work by forcing it against the under side of the die-block as an abutment, the cross-head 40 is supported upon a second vertically movable cross-head 45 by screw mechanism 46, which may be rotated to raise the lever and jack by connections 48 to a treadle 50. Final clamping pressure is created by contacting cams 52, 52 rotatable upon the cross-head 45 and 55

a cross-bar 53 of the frame by connections 54 to the side-rods 12. This final pressure is applied during the beginning of the power-cycle of the apparatus.

5 Taking up the portions of the machine with which our invention is especially concerned, the die D is best shown in Figs. 5 and 7. It has a central body-portion 60 received in opposite ways 62, 62 in the frame (Fig. 1) and normally retained in operating position by pivoted latches 64, 64. Secured to the body-portion 60 by screws 66 is an upper plate 68 and a lower plate 70. Through these plates are vertically alined portions of the passages 24, there being an intermediate space 72 in the body-portion. Depending from the under side of the plate 70 and surrounding the lower portions of the passages 24 are frusto-conical projections 73. These are preferably of such a length, that, when pressed into the yieldable material of a lift, their ends will lie close to its layer of reinforcing material. They thus furnish guides for the flexible fastenings, which are prevented from being deflected laterally from the pricked openings. Further, 25 they may be arranged to enter the fastening-receiving depressions which are formed in many rubber lifts and correctly register said lifts for the fastening-inserting operation. From the lower plate rise guide-tubes 76, these passing 30 through openings in the lower portion of the body 60 and terminating at the space 72. The upper plate 68 is extended rearwardly at 78 to furnish a fastening-shearing portion, in which are openings 80 repeating the design of the passages 24. Into these openings project sections 82 of flexible tubes through which strings f of fastening-material are delivered. This material is preferably of fiber, as that disclosed in Letters Patent of the United States No. 1,729,169, La Chapelle, September 24, 1929.

40 To sever fastenings from the strings of material depending through the openings 80 and supplied by a feeder F, to be hereinafter more particularly described, and to transfer the cut pieces into registration with the passages 24, a loader-block 84 is movable in the space 72. This block is provided with vertical passages 86 arranged in the same design as the passages 24 and the openings 80. In its extreme positions, its 45 passages are first alined with the openings 80 and then with the passages 24. In the former position, the strings are fed into the block-passages to such an extent as will give fastenings of the desired length. Then, as the block travels 50 forward, the meeting faces of said block and the plate 78 co-operate to shear off the ends of the strings to produce a gang of discrete fastenings.

55 Primarily, movement of the block is effected through power furnished by a cam-groove 90 (Fig. 2) formed in the inner face of a gear 92 fast on a shaft 94 journaled in the lower portion of the frame parallel to the shaft 30 and driven therefrom through a pinion 96 meshing with the gear. A lever 98 fulcrumed upon the frame 60 carries a roll 100 lying in the groove 90. This lever at its inner extremity is joined by a rod 102 extending vertically at the rear of the right-hand side-rod 12 (Fig. 4) to a slide 104 guided for vertical movement in the frame near the die-block (Fig. 3). A link 106 connects the slide to the horizontal arm 107 of a bell-crank-lever 108 oscillating about a spindle 110 fixed horizontally across the rear of the frame. A substantially vertical arm 112 of the bell-crank-lever 108 has 75 at its upper end a longitudinal slot 114. A block

116 is adjustable along the slot by opposite screws 118, 118, and a link 120 unites the block 116 with the loader-block 84. In the rearward position of the loader-block, the arm 112 is so inclined, that changing the position of the block 116 by 5 setting the screws 118 will alter the horizontal relation of the loader-block-passages to the plate-openings 80. Thus, correct registration may be obtained. At the opposite extremity of movement of the loader-block, the lever-block 10 116 is so located that its travel in the slot 114 in the arm 112 is about a center which coincides with the pivotal axis of the connection between the link 120 and the loader-block. Therefore, movement of the lever-block will have no effect 15 upon the loader-block. Registration between the loader-block-passages 86 and the die-block-passages 24 may be attained by varying the connections between the cam-roll 100 and the loader-block. For this purpose, there is shown a 20 turnbuckle 121 (Fig. 4) included in the connecting rod 102. As the rod is shortened or lengthened, the loader-block is correspondingly shifted. By these independent adjustments, the loader-block-passages may be accurately alined with 25 both the openings 80 and the passages 24. To more exactly insure that, upon their descent, the drivers will find the loader-block-passages properly positioned to receive them, a stop-screw 125 may pass through the front wall of the die-body 60 (Fig. 7). To avoid injury to the parts when the loader-block strikes the stop, because of excessive movement by its actuating means, and to maintain said block firmly against the stop during the action of the drivers, the lever 30 108 is sectional, the arms 107 and 112 being mounted for relative movement on the spindle 110. To an upward projection from the outer end of the arm 107, a rod 129 is articulated, it passing vertically through an opening in a block 40 131 pivoted upon a rearward projection from the arm 112. At the upper side, a shoulder on the rod is normally held against the block by a spring 133, this spring surrounding the rod between the under side of the block and nuts 135 45 threaded on the lower extremity of said rod. The elements may be so related that when the loader-block 84 engages the stop 125, movement of the arm 112 will continue through a small angle, the spring 133 yielding and offering a 50 resistance determined by the adjustment of the nuts 135. Any positive, harmful pressure of the block against the stop will thus be eliminated, and lost motion in the connections will be taken up. Perfect registration between the loader-block-passages and the die-block-passages may 55 therefore be made certain, and vibration of the loader-block checked. Since, at the opposite extreme of travel, there is no stop for the loader-block, engagement between the rod-shoulder and the block 131 produces positive movement. Something may occur to interfere with the movement of the loader-block. This may be due to the breaking of one or more drivers, broken pieces lying in both the passages 24 and 86. To prevent 60 this from damaging the machine, a frangible element may be included in the connections between the cam-groove 90 and the loader-block. Herein, this is shown as a pin 127 (Fig. 4) joining telescoping sections of the rod 102. This pin 70 is of some relatively soft metal, as brass, and will be sheared off without injury to the other elements if the loader-block meets undue resistance.

The shearing of the plural strings of fastening-material calls for the application of a greater 75

force than can be supplied readily by the connection just described. We therefore provide secondary or auxiliary means for moving the block during the severing period. A collar 122 (Fig. 1) is clamped to the left-hand side-rod 12 and is joined by a link 123 to the forward end of a bell-crank-lever 124 arranged to oscillate about the spindle 110. An upwardly extending arm 126 of the lever 124 is united by a link 128 to one arm of a bell-crank-lever 130 fulcrumed at the left of the frame upon a spindle 132 (Fig. 5). A second arm of the lever 130 carries a roll 134, and this, just as the block 84 leaves its fastening-receiving position beneath the openings 80, contacts with a projection 136 at the rear of the loader-block. This applied intermittently a force of a magnitude ample to sever the ends of all the strings of fastening-material. The cutting action occurs while the side-rod is rising, and the roll 134 is descending. The reverse movement is an idle one, the projection 136 being pivoted to yield upwardly against a spring 137 but being limited in its downward movement to the position illustrated in Fig. 5. The length of the link 128 may be made variable, as by forming it in threaded sections, to permit the time of action of the roll 134 upon the projection 136 to be adjusted.

The drivers 22, which co-operate with the die-block-passages 24 and with the passages 36 when these are aligned with the latter passages in the forward position of the loader-block for the fastening-inserting operation, are a part of a driver-assembly A and are adapted to serve also to prick the work, as a rubber lift, a heel-base and the heel-seat of a shoe in preparation for such insertion. Thus, the elements, which are generally termed drivers throughout the specification, are devices serving a double function and might with equal propriety be called awls. The actuation of the drivers is accomplished in the following manner: Referring to Figs. 1, 5 and 6, there is movable vertically in guides at the front of the top-girt 18, a driver-slide 140, the weight of which is partially counterbalanced by springs 142, 142 connecting it to the top-girt. Threaded vertically into the under side of the slide is a screw 144 having its head circumferentially grooved at 146. Extending into the groove 50 is a projection from a carrier-plate 148, and this guides for a horizontal movement of removal and replacement a compound driver-plate 150 having upper and lower sections. The drivers 22 pass through vertical openings in the lower plate-section and are held in place by the upper, which bears against their heads. The upper plate-section also enters ways in the carrier-plate 148. A spring-latch 152 movable through the driver-plate engages a depression in the carrier-plate to lock the former separably in place. Rotation of the screw 144 permits the vertical relation of the drivers to the work to be altered and therefore the depth to which the fastenings are driven.

Since the drivers must be of a length which will allow them to pass through the die D having considerable thickness, there is best provided near the upper face of said die means for preventing their lateral deflection. This means may consist of a horizontal plate 154 held in place by rods 156, 156 movable vertically through long lugs 157 at the outer corners of the plate 154. The lower ends of the elevated drivers lie in openings 158 in the plate 154, and as they descend during their operation, pass through this 75 and are positively held in alignment with the die-block-passages 24. The plate is arrested by contact with the die-block, the rods 156 rising through the lugs. It will be seen that the driver-plate and the guide-plate furnish a unit which may be removed from the machine by a single act 5 on the part of the operator upon release of the latch 152. The die-block is also preferably made a part of the same unit to insure the proper change of all these elements when the inserting design is to be altered. To this end, a headed stud 160 projects from the front of the die-block and has arranged to turn upon it a link 162. This link passes with substantial clearance through an opening in the front of the guide-plate and has a retaining nut 164 above the 15 plate. As a consequence of this connection, when the die D is freed by the latches 64 and the driver-plate 150 and guide-plate 154 by the latch 152, all must be removed and replaced together, and there is no chance that error in the 20 selection of the proper elements will lead to the breaking of the drivers when the machine is started. The loader-block 84, though capable of replacement, preferably contains a multiple design covering all the insertions which are to be 25 made. Consequently, this will properly co-operate with the openings 80 and 24 in any of the die-blocks.

During the pricking operation, the ends of the drivers, or awls, as they are at that time, must 30 pass through the work substantially to the clinching plate of the last within the shoe being operated upon. When the fastenings are being driven, the driver-ends should reach only to points within the heel, as at the outer surface of a layer of re- 35 infacing material which it contains. Therefore, in the portions of the machine-cycle during which the pricking and inserting operations are performed, the ends of the pricking and inserting devices 22 are held at different levels, and this 40 is effected by shifting the block 140 vertically upon the top-girt. Pivotedly connected to the block and to the girt at the front and rear thereof are toggle-levers 170, 170, the upper links of which are shown as joined by a yoke 172 (Fig. 1). The 45 center of the toggle is united by a link 174 to an upwardly extending arm of a bell-crank-lever 176 fulcrumed at the right of the frame 10. A horizontal arm of the lever is linked at 178 to the slide 104, which, as has been pointed out, is 50 reciprocated through the rod 102 from the cam-groove 90 to actuate the loader-block 84 for transacting the fastening-material. When the lever 176 is turned in a clockwise direction, it acts upon the toggle-levers to carry them to the right, 55 somewhat over the center, against a stop-projection 180 upon the top-girt. Since the toggle mechanism is now substantially straight, this lowers the assembly A and positions the drivers 22 at the proper level for the pricking operation. 60 Opposite movement of the lever 176 shifts the toggle to the left, movement in this direction being limited by engagement of the upper end of the screw 144 with the horizontal wall of the top-girt above it. This elevates the driver-assembly 65 into inserting position. Because the rod 102 must travel for the shearing actuation of the loader-block by the lever 124 through a greater distance than is necessary for the locating of the drivers, the movement for breaking the toggle mechanism 70 is transmitted through a spring 182. To avoid injury to the drivers and to the last within the shoe being operated upon, if said drivers are carried into contact with the last-plate, springs 186 75 are interposed between the top-girt and nuts 184.

threaded upon the upper extremities of the side-rods 12. Consequently, any excess of movement of the drivers will be observed by the springs without breakage of the machine-parts or puncturing of the last-plate.

There may be in the bottoms of some types of shoes, elements through which it is not desired to extend the fastenings. An example of this is found in metal shank-reinforcements which extend back into the heel-seat. We provide for controlling the driver-assembly under such conditions. In the present embodiment of the invention, two drivers 188, 188 (Fig. 6) for the inner breast-fastenings are arranged to prick to a less depth than the companion drivers. These two drivers 188 are carried by a slide 190, movable vertically in ways in the plate 150 but held normally up to an extent determined by the engagement of opposed shoulders 192 upon the slide and plate. This elevation is effected by springs 194 interposed between the slide and a bridge-bar 196 across the front of the plate. The drivers 188 are shorter than the others, being of such a length that they will not strike the reinforcement in performing their function as awls. When, however, they are to insert the fastenings, their ends should lie in the same horizontal plane as those of the drivers 22, since the outer ends of all the fastenings should bear the same relation to the tread-surface of the heel. To bring this about, there is threaded vertically into the top of the slide 190, a screw 200 lying beneath a contact-bar 202 secured to the top-girt across the outer side of the driver-assembly. The screw is so adjusted that when the toggle-levers 170 are broken for the driving stroke, and the driver-assembly is lifted thereby, the bar 202 is engaged by the screw-head, and the drivers 188 are held with their lower ends alined horizontally with the drivers 22.

As the basic machine of Patent No. 446,885 is designed, unless steps are taken to prevent it, the clutch 34 would be thrown out after the power-shaft 30 had turned over once, so the second or inserting portion of the operating cycle would be lost. Moreover, the cams 52, after their first application of pressure to the work, would assume positions in which this pressure would be removed, so, between the halves of the cycle, said work might be displaced, the pricked openings passing out of registration with the die-block-openings 24. We guard against both these difficulties. In the outer face of the gear 92 there is a cam-groove 206 receiving a roll 208 upon an arm 210 fast on the inner end of a spindle 212 extending from front to rear of the machine (Figs. 2 and 4). The hub of the arm 210 carries a cam-incline 214, and this, at the end of the first half of the cycle, moves into the path of the clutch-lever 38, retaining this against movement and thus holding the clutch engaged. At the outer or forward extremity of the spindle 212 is a short, upwardly projecting retaining arm 216. After pressure has been applied to the work in preparation for pricking, the end of this arm is carried under a contact member 218 secured to the cross-head 45 of the upper cam 52. This holds the pressure between the halves of the cycle. At the completion of the full cycle, the cam-groove 206 releases both the clutch and pressure mechanisms.

To increase the holding power of the fastenings, it may be desirable to moisten them prior to their insertion. This activates the adhesive in the material and tends to cause the fastenings to swell. As shown in Fig. 7, a groove or channel

222 is formed in the lower die-block-plate 70 surrounding the tubes 76. This channel is connected by short channels 224 to openings 226, of which there is one through the wall of each tube. The channel 222 is joined by a channel 228 and a pipe 230 to the cylinder 232 of a pump P (Figs. 3 and 9) supported upon the frame above the lever 108 which acts upon the loader-block. The cylinder is supplied with water or other activating liquid through a pipe 234, and in said cylinder a piston 236 is arranged to reciprocate across the port to which delivers the pipe 234 and toward the port of the pipe 230, which is near the lower extremity of the cylinder. The piston is acted upon by a spring 238 surrounding its rod 240, this tending to force it down. It is raised by engagement of the lever 108 with the lower end of the rod and is temporarily held above the port of the pipe 230 by a spring-actuated latch 242 pivoted upon the cylinder and engaging a collar 244 secured to the cylinder-rod. From a tail of the latch there is a lateral projection 246 extending into a longitudinal slot in a link 248 articulated to the lever 108. When this lever is swung in a counterclockwise direction (Fig. 3), at which time the lever-block 84 is being advanced to sever the fastenings and deliver them to the die-block, a screw 250, adjustable as to position in the link, strikes the projection 246 and withdraws the latch from beneath the collar. Thereupon, the spring forces down the piston 236 and urges through the pipe 230 the water which has filled the cylinder from the pipe 234. This occurs at a time when the upper ends of the tubes 76 of the die-block are closed by the drivers. Not having an opportunity to enter freely the tubes which are nearest the delivery-opening of the pipe 230, the charge of water distributes itself along the channels in the die-plate 70 and through the openings 226 into the sections of the die-block-passages which are within the tubes 74, to which are delivered substantially uniform amounts. As the fastenings are advanced by the drivers through the passages, they receive a coating of water which has spread over the inner walls of the tubes. The quantity of water thus supplied may be varied by changing the downward movement of the piston, as by contact of the collar 244 with the head of a stop-screw 252 threaded into the upper end of the cylinder. When the lever 108 tilts in a clockwise direction, as the loader-block is returned to its fastening-receiving position, its engagement with the lower extremity of the piston-rod elevates the piston to its normal relation for retention by the latch 242.

The strings of fiber *f* from which the fastenings are to be formed are supported at opposite sides of the feeder F, upon reels 260 mounted side by side on spindles 262, 262 projecting horizontally from the top of the frame 10 (Figs. 3 and 5). Each string passes downwardly from its reel through a passage to receive the action of a feeding pawl 264 and then through a second passage where a retaining detent 266 contacts with it (Figs. 6 and 8). These string-engaging elements may be in form and effect substantially as is disclosed in Letters Patent of the United States No. 1,849,253, La Chapelle, March 15, 1932, and they will now be described only as to their mounting and actuation. The detents are pivoted in a horizontal series, one for each string, upon a feeder-frame 268, which is mounted at the back of the main frame. With exceptions to be noted later, the pawls are pivot- 75

ed in a series parallel to the plane of the detents upon a carrier 270, extending at opposite sides of a portion 272 of the feeder frame and arranged to slide vertically thereon. Resting in 5 a bore in the frame-portion 272 is a spring 274 which at its upper end contacts with an overhanging projection 276 from the pawl-carrier. This spring maintains the carrier and its pawls normally raised to an extent determined by a 10 horizontal arm 278 at the bottom of the carrier, this arm being yieldably held by the spring against the frame-portion 272. Upon the rear of the slide 140 included in the driver-assembly A is an arm 280 (Fig. 1), the upper end of which 15 is drawn against one side of the toggle-lever 170 by a spring 282 joining it to the slide. Through the upper portion of the arm is threaded a substantially vertical screw 284. During the prick- 20 ing stroke of the driver-assembly, the lower end of the screw is vertically aligned with the upper face of the carrier-arm 278 (Fig. 5) and, during the later portion of the stroke, contacts with said arm and lowers it against the force of the spring 274. This causes the descent of the carrier and 25 with it the pawls 264. These grip the strings and advance them into the loader-block 84 to an extent determined by the adjustment of the screw 284. When the carrier rises, under the influence of the spring during the completion of the prick- 30 ing stroke, the strings are held against retraction by the detents 266. From the detent-passages in the feeder-frame 268, the strings are directed through flexible tubes 288 which terminate in openings through a foot-plate 290. Depending 35 from the foot-plate-openings in registration with the ends of the tubes 288 are the short tubes 82 which enter the openings 80 in the rear portion 18 of the plate 68. In this manner, the strings are continuously guided and are fed to such distances into the passages 86 of the loader-block that they will be sheared off in the proper lengths when that block makes its delivering advance. Of course, during the second or inserting 40 stroke of the drivers, the feeder F should be inactive. This is provided for by so arranging the arm 280 that when the toggle breaks, it strikes the upper end of the arm and swings it to the left (Fig. 1) until its screw 284 is removed from above the carrier-arm 278. Consequently, 45 this stroke of the arm 280 under the influence of the driver-assembly is idle. It may be desired to operate the machine, as in connection with the making of adjustments, without causing the feeder to advance the strings. To allow this, the 50 arm 280 has connected to it by a slot-and-screw connection 289 a stop-plate 291. This may be so adjusted upon the arm, in a direction from front to rear of the machine, that it will either be clear of or will strike the edge of the driver-slide 140. Consequently, the arm will either act as just described or will be so retained that it will not engage the arm 278. In the latter case, 55 there will be no feed.

To enable the operator to make readily the 60 change of the die-block D for different inserting designs, the tubes 82 must be lifted from the plate-openings 80 to be reinserted in the new block-openings. This we accomplish without special effort on the part of the operator by making it an incident to the change of the block. 65 The foot-plate has two laterally extending arms 294 (Fig. 1) from the outer ends of which rods 296, 296 project upwardly, these rods being guided at 298, 298 upon the frame. To the 70 right-hand rod is connected a link 300 which,

at its lower extremity, is joined to a crank-pin 302 revolvable by the pivot of the right-hand latch 64 for the die-block. When the latch is turned to release the block, the crank-pin lifts the link and therefore the foot-plate, so the lower ends of the tubes 82 are raised above the plate-portion 75 78. When the applied block is latched, the tubes descend to be received by its openings 80. The tubes may be caused to find their way into these openings for all inserting designs, by forming 10 about the upper portions of said openings depressions 304 of generally conical form. The tubes occupy mean positions with respect to the various designs and, by contact of their ends with the walls of the depressions, are guided thereby 15 into registration with the openings.

Reference has already been made to the prick- 20 ing of certain of the fastening-receiving openings in the work to a less depth than the companion openings so as to avoid striking shank-reinforcements. Obviously, the fastenings which are to be inserted in these openings should be similarly shortened. To bring this about, special mountings are provided for the feeding pawls which act upon the strings from which these fastenings are to be produced. Most clearly appearing in Figs. 6 and 8, these pawls, as those for the two central breast-fastenings, are carried by individual, secondary slides 310 movable vertically in the primary slide or carrier 270. Each 25 slide is held normally down by a spring 312 interposed between it and the primary carrier. Its upper end is vertically aligned with a stop-screw 314 threaded through a supporting yoke 316 arranged to slide horizontally upon the portion 272 30 of the feeder-frame and limited in its travel by screws 320 passing through slots in the yoke threaded into the frame-portion 272 (Fig. 3). Upon idle elevation of the main carrier 270 by the arm 280 in preparation for the feeding stroke, 35 the slides 310 contact with the screws 314, and their upward travel is arrested before the movement of the main carrier is completed. Consequently, when the downward feeding travel occurs, the pawls of the secondary slides will have 40 effective feeding engagement with the strings for a shorter time than do the companion pawls, and the lengths of the fastening-material delivered by them to the loader-block will be reduced proportionately. When the two breast-fastenings are to 45 be shorter than the others, as just described, the yoke 316 occupies a forward position, so that the screws 314 receive contact of the slides. If no fastenings are to be supplied by the individual units, the yoke is moved rearwardly until the 50 screws are at one side of the slides. In either location, the yoke with its screws may be secured by a spring-plunger 322 movable in the frame-portion 272 and entering either of two depressions 324 in the yoke. To supply all the fastenings of the gang of the same length, the screws 314 are backed off until the pawls of the slides 310 act through the desired length of stroke.

Assuming that the machine is to be utilized 55 for the securing of rubber lifts to heel-bases already attached to shoe-bottoms, the operator will mount a shoe with its base upon the jack 42 and will insert a rubber lift between the spaced arms of a forked plate 330 secured to the under side of the die-block D (Figs. 1 and 5). This plate 60 may have turning about vertical spindles in its opposite arms, rolls 332, 332, the peripheries of which may be knurled to increase their retentive effect. The space between the rolls is such that 65 they slightly indent the rubber to hold the lift 70 75

securely in place. To avoid mutilation of the lift-wall, when pressure is applied to the work and the lift rises against the die-projection 73, the rolls are permitted to shift longitudinally of 5 their supporting spindles. Consequently, there is no relative movement between the lift and the portion of the retaining means which contacts with and might mar it. The back-stop 44 determines the relation of the heel-base upon the 10 jacked shoe to the thus-supported lift. Depres- 15 sion of the treadle 50 will raise the jack by means of the screw mechanism 46 until the lift is pressed against the plate 70 of the die-block, the guide-projections 73 entering the lift. The 20 operator then throws down the hand-lever 36, tripping the clutch 34 and initiating a single power-cycle of the machine. The toggle-lever 170 being straightened, the driver-assembly A, with its devices 22 and 188, is so lowered that 25 said devices will pass through the work into the heel-seat of the shoe to perform the pricking operation. During a portion of this movement of the driver-assembly, it causes the arm 280 to lower the carrier 270 of the feeder F with its 30 pawls 264 to deliver fiber strings f from the reels 260 through the tubes 288, openings of the foot-plate 290, tubes 82 and the rear die-block-openings 80 into the passages 86 in the loader-block 84 to an extent equal to the desired length of the 35 fastenings. The detents 266 prevent the retraction of the strings. After the pricking has been performed, the driver-assembly rises, and the loader-block is advanced by the lever 108 actuated by the cam-groove 90. In co-operation with 40 the portion 78 of the die-block, the ends of the strings in the loader-block-passages are sheared off, extra force to accomplish this being applied by the lever 130 joined to the side-rod 12. At the forward extremity of movement of the loader- 45 block, its passages containing the fastenings are in registration with the die-block-passages 24, and here the loader-block rests while the drivers 22 and 188 make their inserting stroke. The fastenings remain in the block-passages without 50 being displaced by gravity because of the curvature of the cut pieces resulting from the winding of the strings in coils. This curvature causes the fastenings to exert some lateral pressure against the passage-walls. Between the pricking and 55 driving halves of the cycle, the clutch 34 is held engaged and the clamping pressure upon the work is maintained under the control of the lever 210 and the cam-groove 206. In preparation for the driving, the lever 176 actuated from the cam-groove 90 breaks the toggle 170 to lift 60 the lower ends of the drivers from the pricking to the driving plane. This toggle-movement swings the feed-arm 280 to an inactive position, so a double delivery of fastenings during a single 65 cycle is prevented. The drivers now perform their second reciprocation and contacting with the fastenings in the loader-block, drive these out through the passages in the plate 70 into the pricked openings in the work. In their travel 70 through the plate-tubes 76, the fastenings are moistened by the water delivered intermittently by the pump P to increase their holding power. Upon the elevation of the driver-assembly after the driving stroke, the elements of the machine 75 are restored to their initial positions ready for the succeeding operation, and the shoe and heel with the attached lift may be removed from the jack. If there are interfering objects in the shoe-bot- 75 tom, as a shank-reinforcement, which would be struck by full-length drivers, shorter drivers may

be used at this location so they will not reach the reinforcement. Yet, they may be caused to drive the upper ends of the fastenings to the same extent as do the other drivers by mounting them upon the slide 190 in the driver-assem- 10 bly and changing the vertical position of the slide under the control of the bar 196. At the same time, the corresponding fastenings may be shortened proportionately by feeding them through the action of the slides 310, movable independ- 15 ently of the main carrier 270 and governed as to the lengths which they feed by the stationary screws 314. If the inserting design is to be altered, the driver-assembly A, the guide-plate 154 and the die-block D may be changed as a unit 20 because of the connections at 156 and 162. Further, when the die-block-latches 64 are released, the connections 300 simultaneously elevate the foot-plate 290 to separate the tubes 82 from the die-block-openings 80 and thus free said block 25 for removal.

Having described our invention, what we claim as new and desire to secure by Letters Patent of the United States is:

1. In a heel-attaching machine, a movable 30 shoe-support, a heel-abutment provided with passages, means for moving the support with a supported shoe to press a heel against the abutment, means for feeding strings of material, severing fastenings from the strings and delivering them to the abutment-passages, and a device operating in each passage for first pricking the heel and then driving the fastenings from the 35 passages into the pricked openings in the heel.

2. In a heel-attaching machine, a movable shoe-support, a heel-abutment provided with 40 passages and a rearward extension in which are openings, means for moving the support with a supported shoe to press a heel against the abutment, means for feeding strings of fastening- 45 material through the abutment-openings, means for severing fastenings from the strings and carrying them forward into alinement with the abutment-passages, and a device operating in each 50 passage for first pricking the heel and then driving the fastenings from the passages into the pricked openings.

3. In a heel-attaching machine, a movable shoe-support, a heel-abutment provided with 55 passages, a heel-holder situated beneath the abutment in co-operation with the passages, means for moving the support with a supported shoe to press a heel in the holder against the abutment, means for feeding strings of material, severing fastenings from the strings and delivering them to the abutment-passages, and a device 60 operating in each passage for first pricking the heel and then driving the fastenings from the passages into the pricked openings in the heel.

4. In a heel-attaching machine, a die provided with driver-passages and having a rearwardly extending portion in which are openings, a jack movable to press a jacked shoe and a heel against the die, tubes extending into the die-openings, means for feeding strings of fastening-material 65 through the tubes and the openings, a loader-block provided with passages receiving the ends of the strings and cooperating with the die-ex- 70 tension to sever fastenings from the strings, means for moving the loader-block forward to deliver the fastenings into alinement with the die-block-passages, and an assembly having drivers movable through the die-passages while the loader-block is in its rear position to prick the 75 heel, the drivers then being movable through the 75

die-passages and the alined loader-block-passages to drive the fastenings into the pricked heel.

5. In a heel-attaching machine, a die provided with driver-passages and having a rearwardly extending portion in which are openings, a jack movable to press a jacked shoe and a heel against the die, tubes extending into the die-openings, means for feeding strings of fastening-material through the tubes and the openings, a loader-block provided with passages receiving the ends of the strings and cooperating with the die-extension to sever fastenings from the strings, means for moving the loader-block forward to deliver the fastenings into alinement with the die-block-passages, and an assembly having drivers movable through the die-passages while the loader-block is in its rear position to prick the heel, the drivers then being movable through the die-passages and the alined loader-block-passages to drive the fastenings into the pricked heel, the movement of the driver-assembly being communicated to the feeding means to actuate it.

6. In a fastening-inserting machine, a frame, vertical side-rods movable therein, fastening-drivers reciprocated by the side-rods, a die-block supported upon the frame between the side-rods and provided with a rearward extension, there being passages in the forward portion of the die-block to receive the drivers and corresponding openings in the extension to receive fastening-material, a feeder mounted at the rear of the frame and having tubes delivering to the extension-openings, and a loader-block movable upon the die-block and having passages arranged for registration with both the die-block-openings and passages.

7. In a heel-attaching machine, a heel-abutment provided with passages, a heel-holder cooperating with the abutment-passages, a shoe-support movable to press a heel in the holder against the abutment, a shearing device associated with the abutment and having passages corresponding in design to the abutment-passages, a transferring device having passages movable from registration with the passages of the shearing device into registration with the abutment-passages, means for feeding strings of fastening-material into the registering passages of the shearing and transferring devices, means for moving the transferring device to sever fastenings from the strings and deliver them to the abutment-passages, and means operating in the abutment-passages for first pricking the work and then driving fastenings therein.

8. In a heel-attaching machine, a frame, vertical side-rods movable therein, fastening-drivers reciprocated by the side-rods, a die supported between the side-rods, a shear-plate situated at the rear of the die, there being passages in the die for the reception of the drivers and in the plate for the reception of strings of fastening-material, a feeder delivering strings to the plate-passages, and a loader-block provided with string-receiving and fastening-transferring passages and movable from registration with the plate-passages into registration with the die-passages.

9. A die for fastening-inserting machines comprising a body in which is a space, a plate covering the space at one side of the body, and a plate secured to the body at the opposite side, there being passages formed in the die in accordance with a particular nailing design and opening through the plates and a projection surrounding

each opening in one of the plates, the entire die being separable from the machine as a unit.

10. A die for fastening-inserting machines comprising a body in which is a space, a plate covering the space at one side of the body, and a plate secured to the body at the opposite side, there being passages formed in the die and opening through the plates, a projection surrounding each opening in one of the plates and tubes extending inwardly from the openings to the space in the body. 10

11. A die for fastening-inserting machines comprising a body in which is a space, a plate covering the space at one side of the body, and a plate secured to the body at the opposite side, there being passages formed in the die and opening through the plates, a work-engaging projection surrounding each opening at the outer side of one of the plates and tubes extending inwardly from the openings at the opposite side of the plate. 20

12. A die for fastening-inserting machines comprising a body in which is a space, an upper plate covering the space at one side of the body, and a lower plate secured to the body at the opposite side, there being passages formed in the die and opening through the plates, a projection surrounding each opening in the lower plate and the upper plate having an extension in which are openings corresponding to the passages. 30

13. In a heel-attaching machine, a die-block having a body-portion in which is a space, plates secured to the body-portion above and below the space, there being passages formed in the die through the plates and projections surrounding the openings at the outer side of the lower plate, a jack movable to press a shoe which it supports against a heel and the heel against the projections, drivers movable in the die-block-passages, and a loader-block movable in the die-block-space. 40

14. In a heel-attaching machine, a die-block having a body-portion in which is a space, plates secured to the body-portion above and below the space, the upper plate extending rearwardly from the body-portion, there being passages formed in the die and corresponding openings in the plate-extension, both the passages and openings being arranged in accordance with a particular nailing design, and a loader-block movable in the die-block-space and having passages registering with both the die-block-passages and the extension-openings, both the die and loader-block being replaceable by corresponding elements to give other nailing designs. 50

15. A die for fastening-inserting machines comprising a body in which is a space closed at one side of the body, a plate secured to the body at the opposite side, there being passages opening at the opposite sides of the die and arranged in accordance with a particular inserting design, and tubes connecting the passages, the entire die being arranged for movement as a unit into and out of its operating position. 60

16. A die for fastening-inserting machines comprising a body in which is a space closed at one side of the body, a plate secured to the body at the opposite side, there being passages opening at the opposite sides of the die and arranged in accordance with a particular inserting design, and tubes connecting the passages, with openings in the walls of said tubes to deliver thereto a liquid supplied to the space in the body. 65

17. In a fastening-inserting machine, a die provided with passages, drivers movable in the 70

passages, a member reciprocable to cut fastenings from fastening-material for reception by the die-passages, primary means for reciprocating the member, and secondary means for moving the member at the time of cutting the fastenings.

18. In a fastening-inserting machine, a die provided with passages, drivers movable in the passages, a member movable to cut fastenings from fastening-material and to deliver said fastenings to the die, means acting to move the member throughout its travel, and means effective to move the member through only a portion of its travel.

19. In a fastening-inserting machine, a frame, a die mounted thereon, a fastening-shearing and -transferring block movable in co-operation with the die, two levers fulcrumed upon the frame, and means individual to each lever for actuating the block.

20. In a fastening-inserting machine, a frame, a die mounted thereon, a fastening-shearing and -transferring block movable in co-operation with the die, two levers fulcrumed upon the frame, one of which has intermittent contact with a portion of the block, a link joining the other lever to the block, and means for oscillating the levers.

21. In a fastening-inserting machine, a die provided with passages, drivers movable in the passages, a member reciprocable to cut fastenings from fastening-material for reception by the die-passages, primary means for reciprocating the member, secondary means for moving the member at the time of cutting the fastenings, and means arranged to vary the movement of the member by one of the means.

22. In a fastening-inserting machine, a frame, a die mounted thereon, a fastening-shearing and -transferring block movable in co-operation with the die, two levers fulcrumed upon the frame, one of which has intermittent contact with a portion of the block, a link joining the other lever to the block, means arranged to vary the point of connection of the link to the lever, and means for oscillating the levers.

23. In a fastening-inserting machine, inserting mechanism, a member movable between a position at which it receives fastenings and a delivering position at the inserting mechanism, actuating means for the member, connections between the actuating means and the member, and a plurality of means included in the connections for varying both the receiving and delivering positions of the member.

24. In a fastening-inserting machine, inserting mechanism, a member movable between a position at which it receives fastenings and a delivering position at the inserting mechanism, actuating means for the member, connections between the actuating means and the member, and means included in the connections for varying one of such positions of the member, said means being ineffective in the other position of the member.

25. In a fastening-inserting machine, inserting mechanism, a member movable between a position at which it receives fastenings and a delivering position at the inserting mechanism, actuating means for the member, connections between the actuating means and the member, means included in the connections for varying one of such positions of the member, said means being ineffective in the other position of the

member, and means arranged to vary said other position.

26. In a fastening-inserting machine, a die provided with passages, drivers movable in the passages, a member movable to deliver fastenings to the passages, an oscillatory lever, a link joining the lever to the member, and means arranged to vary the point of connection of the link to the lever longitudinally of said lever.

27. In a fastening-inserting machine, a die provided with passages, drivers movable in the passages, a member movable to deliver fastenings to the passages, an oscillatory lever, a link joining the lever to the member, and a connection between the link and lever variable in position longitudinally of said lever, the connection in one extreme position being movable about the point of connection of the link to the member as a center.

28. In a fastening-inserting machine, a die provided with passages, drivers movable in the passages, a member movable to deliver fastenings to the passages, an oscillatory lever, a link joining the lever to the member, means arranged to vary the point of connection of the link to the lever longitudinally of said lever, actuating means, connections between the actuating means and the lever, and means arranged to alter the length of a portion of said connections.

29. In a fastening-inserting machine, a die provided with passages, drivers movable in the passages, a member movable to deliver fastenings to the passages, an oscillatory lever, a link joining the lever to the member, a connection between the link and lever variable in position longitudinally of said lever, the connection in one extreme position being movable about the point of connection of the link to the member as a center, actuating means, connections between the actuating means and the lever, and means arranged to alter the length of the last-mentioned connections.

30. In a fastening-inserting machine, inserting mechanism, a member movable between a position at which it receives fastenings and a delivering position at the inserting mechanism, a stop by which registration of the member is produced at one of its extreme positions, actuating means for the member, and connections by which movement is transmitted from the actuating means to the fastening-delivering member, said connections including a portion arranged to yield upon contact of the member with the stop.

31. In a fastening-inserting machine, inserting mechanism, a member movable between a position at which it receives fastenings and a delivering position at the inserting mechanism, a stop by which registration of the member is produced at one of its extreme positions, actuating means for the member, and connections by which movement is transmitted from the actuating means to the fastening-delivering member, said connections including a portion arranged to yield upon contact of the member with the stop and a portion compelling positive movement of the member in the opposite direction.

32. In a fastening-inserting machine, inserting mechanism, a member movable between a position at which it receives fastenings and a delivering position at the inserting mechanism, a stop by which registration of the member is produced at one of its extreme positions, actuating means for the member, connections by which movement is transmitted from the actuating means to the fastening-delivering member,

said connections including a portion arranged to yield upon contact of the member with the stop, and means arranged to vary the resistance of the connections to yield.

5 33. In a fastening-inserting machine, a die provided with passages, drivers movable in the passages, a loader-block having passages in which fastenings are conveyed to the die-passages, a stop by which the loader-block-passages are caused to

10 register with the die-passages, actuating means, and connections between the loader-block and actuating means and including a lever having relatively yieldable arms.

15 34. In a fastening-inserting machine, a die provided with passages, drivers movable in the passages, a loader-block having passages in which fastenings are conveyed to the die-passages, a stop by which the loader-block-passages are caused to register with the die-passages, actuating means, and connections between the loader-block and actuating means and including a lever having relatively movable arms, a rod pivoted to one arm and being guided for movement relatively to the other and a spring interposed between said 25 other arm and the rod.

30 35. In a fastening-inserting machine, a die provided with passages, drivers movable in the passages, a loader-block having passages in which fastenings are conveyed to the die-passages, a stop by which the loader-block-passages are caused to register with the die-passages, actuating means, and connections between the loader-block and actuating means and including a lever having relatively movable arms, a rod pivoted to one 35 arm and being guided for movement relatively to the other and a spring interposed between said other arm and the rod on one side, the rod acting positively upon such arm on the other side.

36. In a fastening-inserting machine, a die provided with passages, drivers movable in the passages, a loader-block having passages in which fastenings are conveyed to the die-passages, a stop by which the loader-block-passages are caused to register with the die-passages, actuating 40 means, connections between the loader-block and actuating means and including a rod provided with telescopic sections, and a frangible connection between the rod-sections.

37. In a fastening-inserting machine, a die provided with passages, drivers movable in the passages, a member reciprocable to cut fastenings from fastening-material for reception by the die-passages, and an actuating lever having a portion movable into engagement with the member at the 55 time of cutting the fastenings.

38. In a fastening-inserting machine, a die provided with passages, drivers movable in the passages, a member reciprocable to cut fastenings from fastening-material for reception by the die-passages and provided with a projection arranged to yield in one direction and held against movement on the member in the opposite direction, and a lever having a portion movable in opposite directions into contact with the projection.

65 39. In a fastening-inserting machine, a die provided with passages, drivers movable in the passages, a member reciprocable to cut fastenings from fastening-material for reception by the die-passages, a lever having a portion movable into engagement with the rear of the member at the time of cutting the fastenings, an oscillatory lever, actuating means, connections between the actuating means and lever and including a link, and means arranged to vary the length of the 70 link.

40. In a heel-attaching machine, a frame, a die-block carried thereby, vertical side-rods reciprocable in the frame at opposite sides of the die-block, drivers movable by the side-rods in co-operation with the die-block, a reciprocatory 5 loader-block arranged to sever fastenings from fastening-material and deliver them to the die-block, and connections between the loader-block and a side-rod to actuate said loader-block.

41. In a heel-attaching machine, a frame, a die-block carried thereby, vertical side-rods reciprocable in the frame at opposite sides of the die-block, drivers movable by the side-rods in co-operation with the die-block, a reciprocatory 10 loader-block arranged to sever fastenings from fastening-material and deliver them to the die-block, a lever having a portion contacting with the loader-block, and connections to a side-rod for oscillating the lever.

15 42. In a fastening-inserting machine, a die, a slide movable toward and from the die, a carrier mounted upon the slide and provided with ways, a plate having upper and lower sections, the upper section being guided by ways, and drivers fixed in the plate with their heads between the 20 sections and co-operating with the die.

25 43. In a fastening-inserting machine, a die, a slide movable toward and from the die, a member adjustable upon the slide toward and from the die, a carrier supported by the member and provided with ways, a plate having a portion guided in the ways, and drivers fixed in the plate and cooperating with the die.

30 44. In a heel-attaching machine, a frame, a die-block mounted thereon, side-rods reciprocable in the frame at opposite sides of the die-block, a top-girt connecting the side-rods, a slide movable vertically upon the top-girt, a plate separable from the slide, and drivers fixed in the plate and co-operating with the die-block.

35 45. In a heel-attaching machine, a frame, a die-block mounted thereon, side-rods reciprocable in the frame at opposite sides of the die-block, a top-girt connecting the side-rods, a screw arranged to turn upon the top-girt, a carrier supported by the 40 screw, a plate separable from the carrier, and drivers fixed in the plate and co-operating with the die-block.

46. In a heel-attaching machine, a frame, a die-block mounted thereon, side-rods reciprocable in the frame at opposite sides of the die-block, a top-girt connecting the side-rods, a slide movable vertically upon the top-girt, a screw threaded vertically into the slide and having a slotted head, a carrier having a portion entering the slot, a 50 plate separable from the carrier, and drivers fixed in the plate and co-operating with the die-block.

55 47. In a fastening-inserting machine, a die provided with driver-passages, a plate movable toward and from the die and carrying drivers entering the passages, and a guide-plate movable with the driver-plate and having openings registering with the die-passages and in which the ends of the drivers lie.

60 48. In a fastening-inserting machine, a die provided with driver-passages, a plate movable toward and from the die and carrying drivers entering the passages, and a guide-plate mounted to move with the driver-plate and relatively thereto, said guide-plate having openings registering with the die-passages and in which the 65 ends of the drivers lie.

70 49. In a fastening-inserting machine, a die provided with driver-passages, a plate movable toward and from the die and carrying drivers entering the 75

- tering the passages, rods depending from the driver-plate, and a guide-plate secured to the rods and having openings to receive the drivers.
50. In a fastening-inserting machine, a die provided with driver-passages, a plate movable toward and from the die and carrying drivers entering the passages, rods guided for movement upon the driver-plate, and a guide-plate secured to the rods and having openings to receive the drivers, the guide-plate being movable into contact with the die.
51. In a fastening-inserting machine, a die provided with driver-passages, a set of drivers, and connections between the die and drivers permitting them to be removed from the machine as a unit.
52. In a fastening-inserting machine, a die provided with driver-passages and with fastening-receiving openings, a set of drivers, and connections between the die and drivers permitting them to be removed from the machine as a unit.
53. In a fastening-inserting machine, a die provided with driver-passages, a set of drivers, a guide having openings in which the drivers operate, and connections between the die, the drivers and the guide permitting them to be removed from the machine as a unit.
54. In a fastening-inserting machine, a frame, a die mounted thereon and provided with driver-passages, a driver-assembly reciprocable upon the frame toward and from the die, a driver-plate separable from the assembly and having drivers operating in the die-passages, and connections between the die and the driver-plate permitting them to be removed together from the machine.
55. In a fastening-inserting machine, a frame, a die mounted thereon and provided with driver-passages and having a rearward extension in which are fastening-receiving openings, a driver-assembly reciprocable upon the frame toward and from the die, a driver-plate separable from the assembly and having drivers operating in the die-passages, and connections between the die and the driver-plate permitting them to be removed together from the machine.
56. In a fastening-inserting machine, a frame, a die mounted thereon and provided with driver-passages, a driver-assembly reciprocable upon the frame toward and from the die, a driver-plate separable from the assembly and having drivers operating in the die-passages, a guide-plate having openings through which the drivers pass, and connections between the driver-plate and guide-plate and between the guide-plate and die permitting them to be removed from the machine as a unit.
57. In a fastening-inserting machine, a frame, a die mounted thereon and provided with driver-passages, a driver-assembly reciprocable upon the frame toward and from the die, a driver-plate separable from the assembly and having drivers operating in the die-passages, rods depending from the driver-plate, a guide-plate carried by the rods and having openings through which the drivers pass and an additional opening, and a link pivoted upon the die and passing through such additional opening.
58. In a fastening-inserting machine, a die, a support movable toward and from the die, a driver-assembly movable upon the support, a connecting device between the support and driver-assembly for varying the position of said assembly, actuating means, and connections to the actuating means for shifting the connecting device.
59. In a fastening-inserting machine, a die, a support movable toward and from the die, a slide movable upon the support, a lever joining the slide to the support, actuating means, and means for connecting the actuating means to the lever.
60. In a heel-attaching machine, a frame, a die-block mounted thereon, side-rods reciprocable in the frame at opposite sides of the die-block, a top-girt connecting the side-rods, a driver-assembly movable upon the top-girt and co-operating with the die-block, a toggle joining the driver-assembly to the top-girt, and means for shifting the toggle upon the top-girt to move the driver-assembly between work-pricking and fastening-inserting positions.
61. In a heel-attaching machine, a frame, a die-block mounted thereon, side-rods reciprocable in the frame at opposite sides of the die-block, a top-girt connecting the side-rods, a driver-assembly movable upon the top-girt and co-operating with the die-block, a toggle joined at its opposite extremities to the driver-assembly and to the top-girt, a rotatable cam, and connections actuated by the cam and united to the center of the toggle.
62. In a fastening-inserting machine, a die, a support movable toward and from the die, a driver-assembly movable upon the support, means movable to deliver fastenings to the die, an actuating device, a member movable by the actuating device, connections from the member to the driver-assembly, and connections from the member to the fastening-delivering means.
63. In a fastening-inserting machine, a die, a support movable toward and from the die, a driver-assembly movable upon the support, means movable to deliver fastenings to the die, an actuating device, a member movable by the actuating device, connections from the member to the driver-assembly, and connections from the member to the fastening-delivering means, one of said connections including a yieldable member.
64. In a fastening-inserting machine, a die, a support movable toward and from the die, a driver-assembly movable upon the support, means movable to deliver fastenings to the die, a rotatable cam, a rod reciprocable by the cam, connections to the rod for shifting the driver-assembly, and connections to the rod for moving the fastening-delivering means.
65. In a heel-attaching machine, a frame, a die-block mounted thereon, side-rods reciprocable in the frame at opposite sides of the die-block, a top-girt connecting the side-rods, a driver-assembly movable upon the top-girt and co-operating with the die-block, a toggle joining the driver-assembly to the top-girt, a loader-block reciprocable between a fastening-receiving position and a fastening-delivering position at the die, a rotatable cam, a member movable by the cam, connections to the member for shifting the toggle upon the top-girt to move the driver-assembly between work-pricking and fastening-inserting positions, and connections to the member to move the loader-block.
66. In a heel-attaching machine, a frame, a die-block mounted thereon, side-rods reciprocable in the frame at opposite sides of the die-block, a top-girt connecting the side-rods, a driver-assembly movable upon the top-girt and co-operating with the die-block, a toggle joining the

the driver-assembly to the top-girt, a loader-block reciprocable between a fastening-receiving position and a fastening-delivering position at the die, a rotatable cam, a member movable by 5 the cam, connections to the member for shifting the toggle upon the top-girt to move the driver-assembly between work-pricking and fastening-inserting positions, and connections to the member to move the loader-block, the connections 10 between the member and the toggle including a yieldable link.

67. In a fastening-inserting machine, a die, a driver-assembly movable toward and from the die, an operating member from which such movement is imparted to the driver-assembly, and means connecting the operating member to the driver-assembly and including a toggle-lever.

68. In a fastening-inserting machine, a die, a driver-assembly movable toward and from the die through different distances to perform pricking and inserting operations upon the work, an operating member from which such movement is imparted to the driver-assembly, and means connecting the operating member to the driver-assembly and including a toggle-lever, the arms 25 of said toggle-lever assuming a substantially straight relation during the pricking of the work and breaking from such relation for the inserting operation.

69. In a fastening-inserting machine, a movable support, a plurality of drivers carried by the support and having their operating ends lying in different planes, certain of the drivers being movable upon the support, and means for 35 causing the last-mentioned drivers to move until the operating ends lie in substantially the same plane as the ends of the other drivers.

70. In a fastening-inserting machine, a movable support, a plurality of drivers carried by 40 the support and being of different lengths, the shorter drivers being movable upon the support, and means for causing such shorter drivers to move until the operating ends lie in substantially the same plane as the ends of the other drivers.

71. In a fastening-inserting machine, a movable support, a set of work-pricking and fastening-inserting devices carried by the support, a portion only of the devices being movable upon 45 the support, and means for causing such movable devices to assume different positions for pricking and inserting.

72. In a fastening-inserting machine, a reciprocating plate, drivers fixed in the plate, drivers movable upon the plate, and a stationary member arranged to arrest the movement of the 55 drivers with the plate during a portion of the travel of said plate.

73. In a fastening-inserting machine, a reciprocating plate, drivers fixed in the plate, a slide movable upon the plate, a driver fixed in the slide, and a relatively stationary member with which the slide contacts during movement 60 of the plate.

74. In a heel-attaching machine, a die-block, a plate movable vertically toward and from the die-block, a set of drivers carried by the plate, a slide movable upon the plate, a breast-driver being fixed in the slide, means for holding the slide normally raised with the lower ends of its drivers above those of the companion drivers, and means for lowering the slide upon the plate.

75. In a heel-attaching machine, a die-block, a plate movable vertically toward and from the die-block, a set of drivers carried by the plate, means for moving the drivers through successive

pricking and fastening-inserting strokes, a slide movable upon the plate, a breast-driver being fixed in the slide, means for holding the slide normally raised during a pricking stroke with the lower ends of its driver above those of the companion drivers, and means for lowering the slide upon the plate during the driving stroke until the lower ends of the driver lie in substantially the same plane as those of the other drivers. 5

76. In a fastening-inserting machine, a reciprocating plate, drivers fixed in the plate, a slide movable upon the plate, and drivers fixed to the slide. 10

77. In a fastening-inserting machine, a die, a plate movable toward and from the die, drivers fixed in the plate, a slide movable upon the plate, breast-drivers fixed in the slide, and a spring arranged to hold the slide and breast-drivers 15 normally in one extreme position upon the plate.

78. In a fastening-inserting machine, mechanism organized to perform successive work-pricking and fastening-inserting operations during each operating cycle, power means arranged to rotate a plurality of times during each cycle, a member movable by the operator to initiate the 20 rotation of the power means, and means operable by the machine to maintain the member in active position throughout the pricking and inserting portions of the cycle.

79. In a fastening-inserting machine, mechanism organized to perform successive work-pricking and fastening-inserting operations during each operating cycle, a shaft arranged to rotate twice during each cycle, a clutch through which the shaft is rotated, a lever movable under 30 the control of the operator to cause the engagement of the clutch, and a member movable into engagement with the lever under the power of the machine to prevent disengagement of the clutch. 40

80. In a fastening-inserting machine, fastening-inserting mechanism, mechanism for applying pressure to the work, said mechanisms having movable elements and being arranged to operate a plurality of times during each operating 45 cycle, and a member movable by the machine into the path of an element of the pressure mechanism to maintain the pressure upon the work between the operations of said pressure mechanism. 50

81. In a heel-attaching machine, devices movable successively to prick the work and insert fastenings therein, a jack movable to apply pressure to the work during both the pricking and the inserting operations, an actuating member 55 for the jack, said member having two actuating movements during the pricking and inserting cycle, and a retaining member co-operating with the jack to hold the pressure upon the work between the movements of the actuating member. 60

82. In a heel-attaching machine, a frame, a die-block mounted thereon, drivers co-operating with the die-block, a jack to receive a shoe and to press a heel upon said shoe against the die-block, a cross-head movable upon the frame and upon which the jack is supported, a cam acting upon the cross-head and rotatable twice during an operating cycle, and a retaining member movable into engagement with the cross-head during 70 the rotation of the cam.

83. In a fastening-inserting machine, mechanism organized to perform successive work-pricking and fastening-inserting operations during each operating cycle, mechanism for applying 75

pressure to the work, driving mechanism for the machine arranged to rotate a plurality of times during each cycle, mechanism arranged to apply pressure to the work a plurality of times during each cycle, a member movable by the operator to initiate the rotation of the driving mechanism, and means operable by the driving mechanism to maintain the member in active position throughout the pricking and inserting portions of the cycle and to maintain pressure upon the work between the pressure-applications by the pressure mechanism.

84. In a fastening-inserting machine, movable inserting mechanism, a movable work-pressing device, a clutch through which the inserting mechanism and pressing device are moved, and a member movable under the power of the machine to hold the clutch in engagement and to retain the pressing device in its active relation.

85. In a fastening-inserting machine, movable inserting mechanism, a movable work-pressing device, a clutch through which the inserting mechanism and pressing device are moved, and a lever movable under the power of the machine and having a portion acting upon the clutch and a portion acting upon the pressing device.

86. In a fastening-inserting machine, a die provided with a passage, a fastening-driver movable into and out of the passage, means for supplying fastenings to the passage to be driven, and means acting to deliver liquid to the passage when the driver is in and closing the passage to prevent flow of liquid therefrom.

87. In a fastening-inserting machine, a die provided with a passage, a fastening-driver operating in the passage, a member movable to supply fastenings to the passage, a lever for moving the member, and a pump actuated by the lever for forcing liquid to the passage.

88. In a fastening-inserting machine, fastening-drivers, a die provided with passages in which the drivers operate and with a channel furnished by a groove in a surface of the die and extending adjacent to the passages and delivering thereto, and means for delivering liquid to the channel.

89. In a fastening-inserting machine, fastening-drivers, a die provided with passages into and out of which the drivers move and with a channel extending adjacent to the passages, means for delivering liquid to the channel, and means for actuating the delivering means only when the drivers are in and closing the passages to prevent the flow of fluid therefrom.

90. In a fastening-inserting machine, fastening-drivers, a die-body provided with openings, a plate secured to the die-body, said plate having tubes projecting into the openings and furnishing portions of passages in which the drivers operate, said tubes having openings in their walls, a channel formed in the plate adjacent to the tubes and delivering to the tube-openings, and means for delivering liquid to the channel.

91. In a fastening-inserting machine, fastening-drivers, a die provided with passages in which the drivers operate and with a channel furnished by a groove in a surface of the die surrounding the passages and delivering thereto, a pipe joined to the channel, and a pump delivering to the pipe.

92. In a fastening-inserting machine, a die provided with a passage, a fastening-driver operating in the passage, means for supplying fastenings to the passage to be driven, a pump connected to the passage and having a cylinder and a piston movable therein, a spring for moving the piston in one direction, means for moving

the piston in the opposite direction, a latch arranged to hold the piston against the force of the spring, and means for releasing the latch.

93. In a heel-attaching machine, a frame, a die-block mounted thereon and provided with passages, vertical side-rods reciprocating in the frame at opposite sides of the die-block, a bar connecting the side-rods, drivers carried by the bar and operating in the die-block-passages, a horizontal spindle projecting from the frame at the outer side of each side-rod, reels for strings of fastening-material carried by the spindles, and means for advancing the fastening-material simultaneously from both reels to the die-block-passages.

94. In a heel-attaching machine, a frame, a die-block mounted thereon and provided with passages, vertical side-rods reciprocating in the frame at opposite sides of the die-block, a bar connecting the side-rods, drivers carried by the bar and operating in the die-block-passages, a horizontal spindle projecting from the frame at the outer side of each side-rod, reels for strings of fastening-material carried by the spindles, a feeder supported by the frame at the rear of the die-block and between the reels, and a loader-block traveling to and from the die-block and to which the feeder delivers material simultaneously from the reels.

95. In a fastening-inserting machine, a frame, a die mounted upon the frame and provided with passages, drivers reciprocating in the passages, a carrier movable upon the frame, a feeding pawl for fastening-material corresponding to each die-passage and being mounted upon the carrier, and a material-retaining detent mounted upon the frame and cooperating with each pawl.

96. In a fastening-inserting machine, a frame, a die mounted upon the frame and provided with passages, drivers reciprocating in the passages, a carrier movable upon the frame, a member movable with the drivers and actuating the carrier, and a feeding pawl for fastening-material corresponding to each die-passage and being mounted upon the carrier.

97. In a fastening-inserting machine, a frame, a die mounted upon the frame and provided with passages, drivers reciprocating in the passages, a carrier movable upon the frame, a feeding pawl for fastening-material corresponding to each die-passage and being mounted upon the carrier, a spring normally elevating the carrier, and a member movable with the drivers for actuating the carrier to feed the material.

98. In a fastening-inserting machine, a frame, a die mounted upon the frame and provided with passages, drivers reciprocating in the passages, a carrier movable upon the frame, a feeding pawl for fastening-material corresponding to each die-passage and being mounted upon the carrier, a spring normally elevating the carrier, and a member movable with the drivers for actuating the carrier to feed the material, the carrier having a portion which both limits its movement by the spring and receives actuating contact of the member.

99. In combination, fastening-inserting mechanism including a reciprocatory driver-assembly, means for feeding fastening-material to the inserting mechanism, and a member at all times carried upon and reciprocated by the driver-assembly for actuating the feeding means.

100. In combination, fastening-inserting mechanism including a reciprocatory slide and a driver

- mounted thereon, and a fastening-feeder having a reciprocatory member, the driver-slide being provided with a portion contacting with the reciprocatory member to actuate the feeder.
- 5 101. In combination, fastening-inserting mechanism including a reciprocatory driver, means for feeding fastening-material to the inserting mechanism, a member reciprocating with the driver for actuating the feeding means, and 10 means arranged to vary the time of actuation of the feeding means by the member.
- 10 102. In combination, fastening-inserting mechanism including a reciprocatory slide and a driver mounted thereon, a fastening-feeder having a reciprocatory member, the driver-slide being provided with a portion contacting with the reciprocatory member to actuate the feeder, and a screw threaded through such portion of the driver-slide and contacting with the reciprocatory member.
- 20 103. In combination, fastening-inserting mechanism including a device having two operating movements toward and from the work for each operating cycle, a feeder for supplying fastening-material to the inserting mechanism and having a movable element actuated from said device during its travel toward the work for one of its operating movements, and means for preventing the actuation of the feeder during the other operating movement.
- 30 104. In combination, fastening-inserting mechanism including a device having two operating movements for each operating cycle, a member movable with the device, a feeder for supplying fastening-material to the inserting mechanism and having a movable element actuated by contact of the member during one of its operating movements, and means for shifting the member clear of the feeding element during the other operating movement.
- 40 105. In combination, a reciprocatory driver-assembly for inserting fastenings, connections by which the assembly is moved, a feeder for supplying fastening-material for insertion, and an arm pivoted upon the assembly and contacting with a portion of the feeder to actuate it.
- 45 106. In combination, a reciprocatory driver-assembly for inserting fastenings, connections by which the assembly is moved, a feeder for supplying fastening-material for insertion, an arm pivoted upon the assembly and contacting with a portion of the feeder to actuate it, and connections acting upon the arm to move it out of its feeder-actuating position.
- 50 107. In combination, a reciprocatory driver-assembly movable to prick the work and thereafter movable to insert fastenings therein, a toggle-lever through which the assembly is actuated, means for causing the toggle-lever to assume different positions for the pricking and inserting operations, a feeder for supplying fastening-material for insertion, and a member movable upon the assembly and movable thereby to actuate the feeder, the toggle-lever in one of its positions contacting with the member to move it on the assembly to an inactive position.
- 55 108. In combination, a reciprocatory driver-assembly for inserting fastenings, connections by which the assembly is moved, a feeder for supplying fastening-material for insertion, an arm pivoted upon the assembly and contacting with a portion of the feeder to actuate it, and means arranged to be set to prevent movement of the arm to its feeder-actuating position.
- 60 109. In combination, a reciprocatory driver-assembly for inserting fastenings, connections by which the assembly is moved, a feeder for supplying fastening-material for insertion, an arm pivoted upon the assembly and contacting with a portion of the feeder to actuate it, and a plate variable in position upon the arm to limit its movement.
- 65 110. In a fastening-inserting machine, reciprocatory fastening-inserting mechanism having drivers movable successively through different distances to prick the work and to insert fastenings therein, reels for strings of fastening-material, feeding means acting upon the strings to draw them from the reels, and connections to the inserting mechanism for actuating the feeding mechanism, said connections being effective only during the pricking stroke of the drivers.
- 70 111. In a fastening-inserting machine, reciprocatory drivers, a die having fastening-passages with which the drivers co-operate, said die having a portion in which are openings corresponding to the passages, a feeder for fastening-material, a foot-plate situated above the die-openings and having corresponding openings, tubes joining the feeder to the foot-plate-openings, and tubes depending from the foot-plate-openings into the die-openings.
- 75 112. In a fastening-inserting machine, reciprocatory drivers, a die having fastening-passages with which the drivers co-operate, said die having a portion in which are openings corresponding to the passages, a feeder for fastening-material, a foot-plate situated above the die-openings and having corresponding openings, tubes joining the feeder to the foot-plate-openings, tubes depending from the foot-plate-openings into the die-openings, and means arranged to raise and lower the foot-plate.
- 80 113. In a fastening-inserting machine, a frame, a die separable from the frame and having openings, securing means for the die, tubes delivering fastening-material to the openings, and connections between the securing means and the tubes arranged during the release of the die from the frame to separate the tubes from the die-openings.
- 85 114. In a fastening-inserting machine, a frame, an inserting die separably mounted upon the frame and having a set of fastening-receiving passages and a set of corresponding openings, a movable latch for securing the die in place upon the frame, a feeder for fastening-material, a movable foot-plate, tubes connecting the feeder and foot-plate and said foot-plate and the die-openings, and connections between the latch and foot-plate arranged to cause the movement of one to be communicated to the other.
- 90 115. In a fastening-inserting machine, a frame, an inserting die separably mounted upon the frame and having a set of fastening-receiving passages and a set of corresponding openings, a pivoted latch for the die, a feeder for fastening-material, a movable foot-plate, tubes connecting the feeder and the foot-plate and said foot-plate and the die-openings, and a link movable by the pivot of the latch and joined to the foot-plate.
- 95 116. In a fastening-inserting machine, mechanism having devices for inserting fastenings to different depths for a single inserting operation, and a feeder for fastening-material having means for advancing different lengths of said material to the inserting mechanism.
- 100 117. The combination with mechanism having devices for inserting fastenings to different depths, of a feeder for fastening-material having

a movable primary feeding member, a secondary feeding member movable upon the primary member and means for moving the secondary member and primary member relatively.

118. The combination with mechanism having 5 devices for inserting fastenings to different depths, of a feeder for fastening-material having a movable primary feeding member, a secondary feeding member movable upon the primary member, means for moving the secondary member 10 and primary member together to feed the material and means for limiting the reverse movement of the secondary member.

119. The combination with mechanism having 15 devices for inserting fastenings to different depths, of a feeder for fastening-material having a movable primary feeding member, a secondary feeding member movable upon the primary member, means for moving the secondary member 20 and primary member together to feed the material and a normally fixed but adjustable stop with which the secondary member contacts upon reverse movement.

120. The combination with mechanism having 25 devices for inserting fastenings to different depths, of a feeder for fastening-material having a movable primary feeding member, a secondary feeding member movable upon the primary member, means for moving the secondary member and primary member together to feed the material 30 and a normally fixed stop movable into and out of the path of the secondary member.

121. In a fastening-inserting machine, a frame, mechanism having devices for inserting fastenings to different depths, a primary slide movable 35 upon the frame, and a secondary slide movable upon the primary slide, said slides being provided

with pawls for engagement with fastening-material.

122. In a fastening-inserting machine, a frame, mechanism having devices for inserting fastenings to different depths, a primary slide movable upon the frame, a secondary slide movable upon the primary slide, said slides being provided with pawls for engagement with fastening-material, and a stop-screw carried by the frame and with which the secondary slide may contact. 5 10

123. The combination with a frame, of mechanism having devices for inserting fastenings to different depths, a primary slide movable upon the frame, a secondary slide movable upon the primary slide, said slides being provided with 15 pawls for engagement with fastening-material, and a member movable upon the frame and having a portion which may be carried into and out of the path of the secondary slide.

124. In a heel-attaching machine, fastening- 20 inserting mechanism including a die-block, opposite spindles extending from said die-block, and members movable longitudinally of the spindles and arranged for retaining contact with a heel-portion. 25

125. In a heel-attaching machine, fastening- inserting mechanism including a horizontal die-block, a plate secured to the under side of the die-block and having opposite forked arms, a spindle depending from each arm, a roll rotatable 30 about and movable longitudinally of each spindle, the peripheries of the rolls being spaced from each other to receive between them a rubber lift, and means for pressing the lift against the die-block. 35
